Primary Examiner — Wan Laymon(74) *Attorney, Agent, or Firm* — Evan Feldstein(57) **CLAIM**

I claim the ornamental design for a menstrual cup, as shown and described.

DESCRIPTION

FIG. 1 is a perspective view of a first embodiment of a menstrual cup.

FIG. 2 is a top view of the first embodiment of the menstrual cup.

FIG. 3 is a bottom view of the first embodiment of the menstrual cup.

FIG. 4 is a left side view of the first embodiment of the menstrual cup.

FIG. 5 is a right side view of the first embodiment of the menstrual cup.

FIG. 6 is a front view of the first embodiment of the menstrual cup; and,

FIG. 7 is a rear view of the first embodiment of the menstrual cup.

The broken lines are directed to environment and are for illustrative purposes only; the broken lines form no part of the claimed design.
